UNITED STATES PATENT OFFICE

DAVID DOWNER, OF CIMARRON, KANSAS

SCREEN PATCH

Application filed July 13, 1928. Serial No. 292,549.

- This invention relates to a device to be used in repairing screens or the like articles constructed of wire mesh material.
- The primary object of the invention is to provide an article of manufacture in the form of a patch to be positioned over a torn or broken screen to repair the same, the patch closing the opening to prevent insects from passing into the room closed by the screen.
- 10 A further object of the invention is to provide a patch of this character including a supporting member and wire mesh material secured to the supporting member, the supporting member having spurs projecting therefrom, to be positioned within the mesh of the wire mesh material to secure the patch against displacement.
- With the foregoing and other objects in view which will appear as the description 20 proceeds, the invention resides in the combination and arrangement of parts and in the details of construction hereinafter described and claimed, it being understood that changes in the precise embodiment of the invention 25 herein disclosed, may be made within the scope of what is claimed, without departing from the spirit of the invention.
- Referring to the drawing:
- Figure 1 is a fragmental elevational view 30 of a screen repaired with a patch constructed in accordance with the invention.
- Figure 2 is a plan view of the patch.
- Figure 3 is a sectional view illustrating the manner of securing the patch.
- 35 Figure 4 is a fragmental perspective view of the patch.
- Referring to the drawing in detail, the reference character 5 designates wire mesh material mounted in the frame 6, the same being shown as damaged and repaired by a patch constructed in accordance with the invention.
- The patch includes a metallic ring member 7 to which a circular piece of wire mesh material indicated at 8, is soldered or otherwise secured.
- Spurs 9 extend laterally from the ring member 7 and are so constructed that they may be passed within the mesh of the wire mesh material and bent over to lock the ring member in position, it being understood that the spurs 9 are of flexible material to permit of such bending.
- From the foregoing it will be obvious that in order to repair a hole in a screen, it is only necessary to position a repair patch over the hole, and bend the spurs to positions in close engagement with the wire mesh material securing the patch against movement.
- It will further be noted that patches of this character may be manufactured at a comparatively small cost, and may be readily and easily applied, by persons unfamiliar with mechanics.
- I claim:
- A repair patch for screens, including a substantially wide metallic ring member, spurs formed integral with the ring member and disposed adjacent to the outer edge of the ring member, said spurs adapted to be 65 extended through the mesh of the wire screen to which the patch is secured, and wire mesh material welded to the wide metallic ring member.
- In testimony that I claim the foregoing as 70 my own, I have hereto affixed my signature.
- DAVID DOWNER.
